UNITED STATES PATENT OFFICE

95,003

DESIGN FOR A COMBINATION HAND BAG AND BRIEF CASE

Ossip J. Walinsky, New York, N. Y.

Application January 14, 1935, Serial No. 54,838

Term of patent 3½ years

To all whom it may concern:

Be it known that I, Ossip J. Walinsky, a citizen of the United States, and resident of New York city, Borough of Manhattan, in the county and State of New York, have invented a certain new, original, and ornamental Design for Combination Hand Bags and Brief Cases, of which the following is a specification, reference being had to the accompanying drawing, forming a part thereof, and of which Figure 1 is a view in front elevation in completely closed position; Fig. 2 is a perspective isometric view in partially open position, and Fig. 3 is a perspective isometric view on a reduced scale in completely opened position, of a combination hand bag and brief case showing my new design.

I claim:

The ornamental design for a combination hand bag and brief case substantially as shown and described.

OSSIP J. WALINSKY.
